UNITED STATES PATENT OFFICE.

PHILIP MUELLER AND ANTON C. SCHUERMANN, OF DECATUR, ILLINOIS, ASSIGNEES
TO ADOLPH MUELLER, TRUSTEE, OF DECATUR, ILLINOIS.

PEDESTAL DRINKING FOUNTAIN.

Application filed November 12, 1919. Serial No. 337,490.

To all whom it may concern:

Be it known that we, PHILIP MUELLER and ANTON C. SCHUERMANN, citizens of the United States, residing at Decatur, in the county of Macon and State of Illinois, have invented new and useful Improvements in Pedestal Drinking Fountains, of which the following is a specification.

The present invention relates to sanitary drinking fountains, and, as herein shown is of the pedestal type in which the bubbler head and waste bowl are supported on a pedestal, said pedestal being hollow so as to conveniently and properly house the supply and waste pipe connections and the supply valve and its operating parts.

It has for its object to provide a construction in which the parts are compactly disposed in relation to one another; in which the assembling of the parts in setting up the fountain may be accurately and expeditiously done with a minimum number of threaded unions; in which the supply valve and its accessories are readily accessible for necessary adjustment without disturbing the pedestal; and in which supply and waste are efficiently and sanitarily disposed for the delivery and disposal of the water.

No claim is made to the hand hole construction, nor to the particular type of supply valve herein disclosed, since these features are being separately claimed in applicant's copending applications, Serial No. 635,590, filed April 30, 1923, and Serial No. 668,635, filed October 15, 1923, respectively.

In the drawings herewith we have illustrated one embodiment of our invention, and in said drawings:

Fig. 1 is a view, mainly in vertical section, of a fountain disclosing our improvements,

Fig. 2 is a sectional view, on an enlarged scale, of the base and bowl of the fountain with the contained fittings.

Fig. 3 is a top plan view of the base-plate with the lower part of the pedestal in section,

Fig. 4 is a view substantially on line 4—4, Fig. 1,

Fig. 5 is a detail sectional view of the supply valve, operating lever, and regulator screw,

Fig. 6 is a slightly different development

of supply valve and regulator screw, one form of handhole cover plate being shown, 55

Fig. 7 is a view of still another form of supply valve;

Fig. 8 is a vertical sectional view of the lower part of the pedestal and base plate,

Figs. 9 and 10 are sectional and rear 60 elevational views, respectively, of one form of handhole cover plate,

Figs. 11 and 12 are similar views of a slightly different type of cover plate,

Figs. 13 and 14 are front elevational and 65 sectional views of a handhole and pedestal slot cover plate,

Figs. 15 and 16 are plan and vertical sectional views, respectively, of a pedal housing.

In the drawings, in which like numbers refer to like parts in the several views, 10 indicates the templet base-plate which has the apertured waste pipe lug 11 and the apertured supply pipe lug 12 rising 75 therefrom and provided, respectively, with tapped holes for the reception of set-screws 13 which serve to clamp the pipes in fixed position in the base-plate. The base-plate 10 has, also, the pedal receiving lugs 14 and 80 15 on opposite sides thereof to receive and guide the pedal levers. Projecting from the base-plate on either side thereof are the arms 16 each provided with holes 17 to receive lag screws 18 by which the plate is 85 fastened to the floor, and preferably near their outer ends the arms 16 are provided with pins 19 designed to engage pin-receiving recesses formed in the lugs 20 on the bottom of the pedestal 21, so as to furnish 90 a convenient means of locating and centering the pedestal and its parts relative to the waste and supply pipes.

The said templet and base-plate having been positioned at the point where the fountain is to stand, the supply and waste pipes may be located by means of the apertured lugs 11 and 12 and roughed in, after which the base-plate will be set, secured by the lag screws, and the supply nipple section 100 22 and the waste pipe section 23 coupled up to their respective connections (not shown) by any suitable couplings, and clamped in their receiving lugs by the set-screws heretofore described.

In this condition the parts are ready for

the coupling up of the several pipe sections, supply valve and operating parts, and, finally, for the locating and seating of the pedestal and the placing of the basin with its bubbler head and waste.

The waste pipe section 23 has coupled thereto the offset fitting 24 said fitting being provided with a tapped lug or boss 25 to receive a supply pipe connection, the passage through said lug 25 connecting with a vertical passage formed in an interior lug 26 in the fitting, which receives the vertically disposed supply pipe 27 leading to the bubbler head, which supply pipe 27 traverses the upper section 28 of the waste pipe.

The lower supply nipple 22 has secured thereto the cock body 29, which cock body couples, preferably by a slip joint union 30, with the supply pipe section 31, which, by an elbow coupling, connects with the supply pipe section 32 entering the boss 25 on the offset waste fitting 24, as heretofore described.

The cock body 29 has a port therethrough controlled by a valve 33, said valve being normally held to its seat by a spring 34 surrounding the stem 35 of the valve which carries a pin 36 engaging a slot 36' in a stuffing nut 37 to prevent rotation of the sleeve thrust collar 39.

The stem 35 of the valve passes through the stuffing nut 37, which is preferably held against accidental displacement by means of the lock finger 38 which engages the hexagonal periphery of the stuffing nut. The outer end of the valve stem 35 has adjustably secured thereto, preferably by the screw threaded connection shown a flanged sleeve or thrust collar 39 held by a cotter pin 40 engaging a slot in the outer end of the sleeve or nut 39, so that when the sleeve has been adjusted longitudinally of the stem it may be locked against accidental rotation by means of the cotter pin.

The said sleeve 39 is engaged between its flanges by a pedal fork 41 carried by a pedal 42 pivoted at 43 on an arm 44 projecting from the cock body 29, the said pedal arm 42 extending outwardly and terminating in a foot piece 45, the pedal being shown in Fig. 1 in its raised position with its lever portion 42 lying between the guide lugs 15 on the base-plate heretofore referred to.

It will be seen, that, if the foot be applied to the pedal extremity 45 and the pedal lever rocked upon its pivot 43, the fork 41 connected with the adjustable nut 39 will pull the valve 33 from its seat, compressing the spring 34, and permit water to pass from the supply pipe through the cock body, and, by the connections heretofore described, flow to the bubbler head. Upon release of pedal the valve will close automatically to shut off the supply.

In order that the supply may be regu-

lated, or entirely stopped if necessary, there is provided a stop and regulator screw 46 threaded in the cock body opposite the valve seat with its stem passing through a suitable gland 47, the outer end of the stop screw 70 being formed to receive a wrench, so that the screw 46 may be adjusted to regulate the flow or seated to entirely shut off the flow. In order that the stop screw 46 may be held against accidental displacement we 75 preferably provide the lock finger 48 to engage the serrated periphery of the outer end of the stop screw, as shown.

The parts thus described are closely assembled, the offset fitting of the waste pipe 80 bringing that pipe relatively close to the supply pipe, and positioning the upper sections of the waste and supply pipes centrally with respect to the base-plate, to which base-plate all of the parts are secured, and said base-plate, as described, is, in turn, fastened to the floor. As thus assembled the parts are enclosed within the pedestal 21, which pedestal will be accurately located when it is placed upon the baseplate, by the pins 19 which engage the lugs 20, as heretofore described, and the pedestal 21 when thus set will be properly positioned to bring the crescent 50 for the pedal extremity 45 and the slot 51 for the pedal arm in proper relation to that pedal.

On the opposite side of the pedestal there is provided a hand-hole to permit access to the cock body and its assembled parts and the other fittings, and particularly to permit adjustment of the stop and regulator and the valve and pedal parts. This hand-hole will be preferably of the form shown, comprising the circular aperture 52 and the downwardly extending slot 53, which, where only one pedal, namely, the adult's pedal 45 heretofore described is installed, will be entirely closed by a cover plate 54 having a downwardly extending strip 55 so as to cover both the circular opening 52 and the slot 53 as shown in Fig. 13. The said cover plate will be preferably of the form shown in Fig. 14 with the upper portion 54 having a flanged wrench receiving screw 56 which engages the crossbar 57, the screw 56 having at its inner end the flanged head so as to prevent the crossbar from dropping off when screw is loosened to remove cover plate. Said crossbar, when brought to a vertical position, may be inserted through the hand-hole 52, its upper end entering the recess 58 formed in the pedestal and its lower end entering through the slot 53. When the crossbar is in this position and a wrench is applied to the square end of the screw 56 the crossbar will be turned to the position shown in Fig. 13 with its ends engaging the inner wall of the pedestal and taking bearing upon the lugs 59 formed on the inner wall, and continued rotation of the screw 130

56 will then clamp the cover plate closely to the outer wall of the pedestal, closing the hand-hole and slot. It will be observed that the stop and regulator 46 is in line with the hand-hole, and preferably we provide a single wrench for rotating the screw 56 for the cover plate and the stop and regulator 46, the wrench receiving formation of these two parts being the same so that the necessity for different wrenches for manipulating these two parts is done away with.

It is desirable in some installations to provide, in addition to the adult's pedal a pedal device and stand for children who are 15 unable to reach the bubbler head from the ground. In order to adapt the fountain to the use of children as well as adults without the necessity of changing the essential parts of the equipment or the fittings, we provide 20 a second valve operating pedal 60, which is pivoted at 61 to a projection on the cock body, the pedal 60 being forked as shown so as to straddle the lower part of the cock body and having at its inner end a lifting 25 toe 62 which engages a projection 63 on the adult's pedal 42. The outer end of the child's pedal 60 will project through the slot 53, the cover plate, where the child's pedal is used, being merely a circular plate to 30 cover the hand-hole, without the depending strip heretofore described, so as to leave the slot 53 open for the outer end of the pedal 60 which will project through slot and into the crescent 64 preferably formed at the base 35 of the pedestal. It will be seen, that, upon depressing the outer end of the lever of the child's pedal 60, the toe 62 will lift the projection 63 of the adult's pedal 42 and operate the valve exactly as it is operated when the 40 adult's pedal is depressed, but there will, of course, be no operation of the child's pedal when the adult's pedal is manipulated.

The child's pedal 60 has the push rod 65 connected therewith, said push rod terminating at its upper end in a foot button 66 passing through the floor of a child's stand 67, supported upon suitable legs secured to the floor adjacent the pedestal, said stand preferably being recessed at 68 so as to engage 50 pedestal, as shown; the stand thus provided giving the necessary elevation to permit the child to reach the bubbler head, and, through the parts just described, enable him to operate the supply valve.

55 The pedestal 21 after having been placed, as described, is anchored firmly in position by means of a nut 69 fitted to the top of the waste pipe 28 and having a projecting flange 70 to receive the cap screws 71 which 60 bear against a pedestal clamping plate 72, resting upon lugs 73 formed on the inner wall of the pedestal. It will be seen, that after the pedestal has been placed, the clamping plate 72 will be dropped over the waste pipe section 28, the flanged nut 69

threaded to the upper end of the waste pipe, and then, upon setting up the cap screws 71, the pedestal will be clamped firmly in place upon the base plate, to which it is locked against lateral movement by the 70 pins 19.

The cap nut 69 is designed to form a slip joint connection with the bowl waste pipe, being provided with a recess in its head which receives a gasket 74, which protrudes 75 inwardly slightly, and within this cap nut the depending end of the waste pipe 75 will depend, the extreme end being beveled so that it will slip readily into place, and when in position will form a fluid and gas 80 tight joint.

The waste pipe 75 has the connection 76 by means of which it is clamped to the bowl, the screws 77 engaging this connection and clamping it tightly to the bottom of the 85 bowl below the strainer opening, a gasket 78 being interposed to insure a tight joint. The screws 77 serve also to clamp the strainer 79 in place, this strainer being of any approved form, but preferably as shown, 90 having the centrally disposed pipe section 80 as shown, about which are arranged the necessary strainer openings delivering to the waste pipe connection 75, this waste pipe connection being flared at its upper end, as 95 shown, to increase its area to correspond to the area of the strainer.

The bowl with the associated parts just described is dropped into position after the pedestal has been secured and it may be connected to the bowl in any suitable manner, as, for example, by the screws 81, which engage slotted lugs 82 on the pedestal and are tapped into depending lugs 83 on the underside of the bowl and within the bowl 105 skirt.

The bubbler head 84 may be of any desired type and is connected by means of the pipe 85 with the section 27 of the supply pipe, preferably by the screw thread connection shown.

In that form of the invention shown in Fig. 6 a similar construction to that heretofore described is shown, except that no provision is made for the child's device, it being designed to have only the adult's valve-operating pedal 86, and a different type of cover plate is disclosed, the cover plate being of the form of a box 87, the lower end of which is provided with lugs 88, which rests upon the pedestal as shown in Fig. 6 with the upper part of the housing conforming to and enclosing the recess 89 in the pedestal wall, through which the stop and regulator portion of the cock body projects slightly. The cover plate 87 is anchored in place by means of a clamping bar 90, the inner end of which is bent as shown to engage the wall of the pedestal and the outer end of which is seated in a pocket 91 formed 125 130

4 by ribs on the inner side of the cover plate. A clamping screw 92 is tapped through the top of the cover plate and engages the clamping bar 91, so that when the cover plate or housing has been set in position and the clamping bar drawn up by means of the screw, the housing 87 will be locked firmly in place. With this arrangement the cock body and its associated parts are very readily accessible for adjustment and repairs.

5 The stop and regulator shown in Fig. 7 are varied slightly in construction from that heretofore described. It comprises the long screw 93 having a threaded engagement of suitable length with the cock body and being arranged opposite the valve seat. The screw 93 is provided with a notched head 94 adapted to be engaged by a screw locking pawl 95 pivoted on the cock body, so that when the screw 93 has been adjusted the pawl may be dropped into locking engagement to prevent its accidental rotation and eliminate all possibility of disarranging the 25 regulated supply. The stop and regulator thus described are entirely enclosed by means of the cap 96, which is threaded to the cock body as shown, and which is of wrench formation so that it may be turned by hand 30 or a suitable tool or wrench after the cover plate has been removed.

It has been pointed out that where the child's pedal and slotted pedestal are not used, a cover plate having a depending skirt 35 to close the handhole and pedal slot will be used, this form being disclosed in Figs. 13 and 14.

When the child's pedal is not used and the 40 pedestal has simply the handhole, the cover plate may be of the form shown in Figs. 9 and 10, in which a plate 97 of crowned form and having the screw head recess 98 is provided, said plate having disposed centrally thereof a freely rotatable screw 99 with a 45 wrench-receiving head or its equivalent at its outer end. The screw 99 engages at its inner end the inwardly arched middle portion of a locking bar 100, which spans the handhole 101 with its ends bearing against 50 the inner wall of the pedestal. The arched form of bar 100 and the recessed plate 97, bring the parts close together and permit the use of a screw 99 of minimum length, as shown in Fig. 9. The locking bar 100 is 55 permanently held by a flange or head 102 on the screw 99, the flange 103 on the other end of the screw preventing escape of the plate 97, so that the parts cannot become separated and lost.

60 The plate and bar are placed in position by inserting the bar 100 through slots 104 in the periphery of the hand-hole 101, with the plate 97 resting against the outer wall of the pedestal 21. Upon turning the screw 65 99 the bar 100 will be moved to the position

shown in Fig. 10 with the ends of bar 100 bearing against lugs 105, whereupon continued turning of the screw will draw the plate and bar together and clamp them tightly over the handhole. In order to ensure the ready removal of the plate, the lugs 106 are preferably placed adjacent the slots 104, so that when the bar 100 is swung back to remove the cover-plate it will strike the lugs 106, stop in registry with the slots, and may be readily removed without the delay which would occur if it were necessary to rotate the concealed bar in a hit-or-miss fashion until registry of bar and slots was secured.

70 In the construction shown in Figs. 11 and 12, the bar 107 is straight instead of arched, and the cover plate 108 is shallower than in the form just described, with its center dropped into the handhole, as shown in Fig. 75 11. Preferably lugs 109 will be provided on plate 108 to center and lock the plate against rotation. Said plate and bar are coupled by screw 110, the outer end of which is formed to receive any suitable tool and lies within 80 the recess formed in the face of plate 108. The screw 110 passes through the center of bar 107, which is preferably thickened to give sufficient threading area, and is headed at its inner end to prevent complete separation of the parts. Stop lugs 111 will preferably be formed adjacent the slots in the periphery of the handhole, to ensure registering of bar and slots when the cover is removed, and said lugs 111 may serve also, 85 as stops for the bar 107 when it is in locked position, as shown in Fig. 12.

90 Cover plates of this type may be very quickly applied and removed, and their construction is such that not only is cost of production low, but also danger of breakage is practically eliminated. While the particular installation here shown is in connection with a fountain pedestal, it will be understood that these plates may be used in any 105 structure where cover-plates are necessary. Furthermore, they may obviously be of such design and dimensions as are required for the particular work in hand.

110 In the forms of pedestal heretofore disclosed the outer ends of the pedal levers lie in crescents cast in the pedestal wall and are protected from side kicks or strains tending to distort or break them. In some installations a circular pedestal without pedal crescents are used, and in such constructions the 120 pedestals extend radially and unprotected from the pedestal wall. In order to properly protect them under such conditions the construction shown in Figs. 15 and 16 is provided. As there shown the box or housing 112 is provided to cover the projecting pedal. Said housing may be formed integral with the pedestal, or separate therefrom as here shown, and comprises the box- 125 130

like structure, closed at its top, back and sides, and open at its front to permit the foot to be inserted to manipulate the pedal 113, the rear wall of the housing having a slot 114 coinciding with the slot in the pedestal wall to receive the pedal lever 115. Where the housing is separately formed, its rear face will be curved to fit snugly the wall of the pedestal, and suitable securing means are provided, such as, for example, the screw-receiving lugs 116 which may be positioned for attachment to the floor, as shown, or equivalently for attachment to the pedestal wall.

15 It will be obvious that changes in design, and substitution of mechanical equivalents for the various expedients disclosed may be made without departing from the invention herein set forth, and all such departures are, therefore, to be regarded as within the range of the invention.

We claim:

1. The combination, in a drinking fountain, of a pedestal, a waste-pipe having an upper section disposed centrally and a lower section disposed eccentrically of said pedestal, and a supply-pipe having an upper section disposed centrally and a lower section disposed exteriorly of said lower section of the waste pipe.

2. The combination, in a drinking fountain, of a pedestal, a waste-pipe having an upper section disposed centrally and a lower section disposed eccentrically of said pedestal, and a supply-pipe the upper section of which traverses the central upper section of said waste-pipe and the lower section of which is outside of said waste-pipe and disposed eccentrically relative to said pedestal.

3. The combination, in a drinking fountain, of a pedestal, a waste-pipe having a centrally disposed upper section and an eccentrically disposed lower section in said pedestal, and an inclined section connecting said upper and lower sections; and a supply pipe having an eccentrically disposed lower section in said pedestal, a centrally disposed upper section in said waste-pipe, and a section connecting said upper and lower supply pipe sections through the wall of said waste-pipe.

4. The combination, in a drinking fountain, of a pedestal, a waste-pipe having a centrally disposed upper section and an eccentrically disposed lower section in said pedestal, and an inclined section connecting said upper and lower sections; and a supply pipe having an eccentrically disposed lower section in said pedestal, a centrally disposed upper section in said waste-pipe, and a section connecting said upper and lower supply pipe sections through the wall of said inclined waste-pipe section.

5. The combination, in a drinking fountain, of a pedestal, a waste-pipe having off-

set upper and lower sections, and a supply pipe having offset upper and lower sections with the upper supply-pipe section traversing said waste-pipe.

6. The combination, in a drinking fountain, of a pedestal, a waste-pipe in said pedestal having offset upper and lower sections, a supply-pipe in said pedestal having offset upper and lower sections, one of said supply pipe sections entering and traversing one of said waste-pipe sections, and the other of said sections disposed exteriorly of the waste pipe.

7. The combination, in a drinking fountain, of a base, a pedestal located over said base, a basin on said pedestal, a lower waste-pipe section mounted in said base eccentrically of said pedestal, an inclined coupling-section secured to said lower waste-pipe section, an upper waste-pipe section connected to said inclined section and disposed centrally of said pedestal, a lower supply-pipe section mounted in said base eccentrically of said pedestal, an upper supply-pipe section leading to said basin and disposed centrally of said upper waste-pipe section, and an offset connection between said upper and lower supply-pipe sections entering the wall of said inclined coupling section.

8. The combination, in a drinking fountain, of a base, a pedestal, a basin, waste and supply pipes traversing said pedestal and having separated eccentrically disposed lower sections mounted in said base and nested upper sections leading to said basin, a supply-valve in the lower supply pipe section; and means extending from said supply-valve exteriorly of said pedestal to actuate said valve.

9. The combination, in a drinking fountain, of a base, a pedestal, a basin, waste and supply pipe traversing said pedestal and having separated eccentrically disposed lower sections mounted in said base and nested upper sections leading to said basin, a supply-valve in the lower supply pipe section, means extending from said supply-valve exteriorly of said pedestal to actuate said valve, and a second valve-operating means extending outside of said pedestal and operable at a higher level than said first-named operating means.

10. The combination, in a drinking fountain, of a base, a pedestal, a basin, waste and supply pipe traversing said pedestal and having separated eccentrically disposed lower sections mounted in said base and nested upper sections leading to said basin, a supply-valve in the lower supply pipe sections, means extending from said supply-valve exteriorly of said pedestal to actuate said valve, and means extending outside said pedestal engaging said first-named valve-actuating means and operable from a higher level to actuate said valve.

11. The combination, in a drinking fountain, of waste and supply pipes, means controlling said supply, means for actuating said controlling means, and a second actuating means operable from a higher level than said first-mentioned means. 65
12. The combination, in a drinking fountain, of waste and supply pipes, a supply valve, valve-actuating means, and a second valve-actuating means operable from a higher level. 70
13. The combination, in a drinking fountain, of a pedestal, waste and supply pipes in said pedestal, a supply-valve, means for actuating said valve extending outside said pedestal, and a second valve-actuating means extending outside said pedestal and operable from a higher level. 75
14. The combination, in a drinking fountain, of waste and supply pipes, a supply valve, a valve-actuating lever, and a second valve-actuating lever operable from a higher level. 80
15. The combination, in a drinking fountain, of waste and supply pipes, a supply-valve, a valve-actuating lever, and means engaging said lever and operable from a higher level for actuating said valve. 85
16. The combination, in a drinking fountain, of waste and supply pipes, a supply-valve, a valve-actuating lever, and a second lever engaging said first named lever and operable from a higher level for actuating said valve. 90
17. The combination, in a drinking fountain, of waste and supply pipes, a supply-valve, a valve-actuating lever, a second valve-operating lever, and a push-rod extending upwardly from said second lever to permit its operation from a higher level. 95
18. The combination, in a drinking fountain, of waste and supply pipes, a supply-valve, a valve-actuating lever pivotally mounted on the valve body, a second valve operating lever pivotally mounted on the valve body and engaging said first-mentioned lever, and a push-rod connected with said second lever and adapted to be operated from a higher level. 100
19. The combination, in a drinking fountain, of a pedestal, a basin on said pedestal, waste and supply pipes traversing said pedestal, a supply valve in said supply pipe, a valve-actuating lever pivotally mounted on said valve body and extending outwardly through an aperture in the pedestal, a second lever pivotally mounted on the valve body and engaging said first mentioned lever, said second lever extending outwardly through an aperture in the pedestal, a raised platform adjacent said pedestal, and a push-rod extending from said second lever upwardly to said raised platform. 105
20. The combination, in a drinking fountain, of a base, a pedestal, a basin on said pedestal, waste and supply pipes leading from said base to said basin, a supply valve in said supply pipe, a valve-operating lever extending outwardly through an aperture in said pedestal, a second valve-operating lever extending outwardly through an aperture in said pedestal and provided with means contacting with said first mentioned lever for actuating the supply valve, a hand-hole in the wall of said pedestal opposite said valve, and a cover-plate for said hand-hole. 110
21. The combination, in a drinking fountain, of a base, a pedestal on said base, a basin on said pedestal, waste and supply pipes leading from said base to said basin, a supply-valve in said supply pipe, a valve-operating lever extending outwardly through an aperture in said pedestal, a second valve-operating lever extending in an opposite direction from said first-named lever through an aperture in said pedestal provided with means contacting with said first mentioned lever for actuating the supply valve, a working hand-hole at the upper end of said last-named aperture opposite said valve, and a cover-plate for said hand-hole. 115
22. A base plate for drinking fountains having pedestal locating and fastening pins, and waste and supply pipe locating and receiving bosses thereon. 120
23. A base plate for drinking fountains having pedestal locating and fastening pins, waste and supply pipe locating and receiving bosses, and pedal guiding lugs thereon. 125
24. A base plate of substantially cruciform shape having pedestal locating and fastening pins on one set of arms, a waste pipe locating and receiving boss on one of its other arms, and a supply pipe locating and receiving boss on the other arm. 130
25. The combination, in a drinking fountain, of a pedestal having a lever slot therein, a valve-operating lever projecting through said slot, and a housing for the end of said lever. 135
26. The combination, in a drinking fountain, of a pedestal having a lever slot therein, a valve-operating lever projecting through said slot, and a housing for said lever having an open foot-receiving front. 140
27. The combination, in a drinking fountain, of a pedestal having a lever slot therein, a valve-operating lever projecting through said slot, and a housing for said lever fitted to the wall of said pedestal and having an open foot-receiving front. 145
- In testimony whereof we have hereunto set our hands.
- PHILIP MUELLER.
ANTON C. SCHUERMANN.
